THE NORRIS PETERS CO., PHOTO-LITHO., WASHINGTON, D. C.

UNITED STATES PATENT OFFICE.

GEORGE A. ROSS, OF CHICAGO, ILLINOIS.

CUPOLA.

1,272,854.

Specification of Letters Patent. Patented July 16, 1918.

Application filed January 21, 1916. Serial No. 73,323.

To all whom it may concern:

Be it known that I, GEORGE A. Ross, a citizen of the United States, and a resident of Chicago, county of Cook, and State of Illinois, have invented certain new and useful Improvements in Cupolas, of which the following is a specification.

My invention relates generally to improvements in cupolas, and has particular reference to improvements in cupolas for instruction purposes.

The demand for instruction in vocational subjects has led to the establishment of many technical and manual training schools of both public and private character where subjects of this kind are taught. Many of these schools are public schools or schools so conducted that pupils enter directly from the grammar school in large numbers and are taught such subjects as pattern making, machine shop practice, foundry practice, etc. It is highly important that the equipment for this purpose shall be simple, and durable, to the end that it may be successfully operated by the student of average ability, and of such nature that a great number of students may be taught with a limited equipment.

The general object of my invention is to provide a cupola, which shall be better adapted for use in schools, than those hitherto devised.

A further object of my invention is to provide a cupola which shall facilitate the work of repairing the lining; and other objects are to provide a cupola, by means of which it shall be possible to show the interior of the working part to a large class of students at the same time, and to demonstrate the general construction of the furnace, the construction and arrangement of the lining, the location of the melting zone, the action of heat and fluxes on the lining, and a method of chipping and daubing the furnace.

Another object of my invention is to provide a cupola for school use which, while especially designed to facilitate instruction, shall also be efficient and economical and capable of producing commercially acceptable iron.

My invention consists generally in the form, arrangement, and construction of parts, whereby the above named objects, together with others which will appear herein-after, are attainable.

My invention will be more readily under-

stood by reference to the accompanying drawings illustrating the preferred embodiment of my invention; and in which—

Figure 1 is a perspective view of the cupola in condition for use.

Fig. 2 is a perspective view similar to Fig. 1 but showing the cupola in condition for easy inspection or repair.

Fig. 3 is a view of the cupola, partly in elevation and partly in section, better to disclose the air supply system.

Fig. 4 is a cross sectional view substantially on the line 4—4 of Fig. 3.

Fig. 5 is a face view of one of the air nozzles.

Fig. 6 is an enlarged detail sectional view substantially on the line 6—6 of Fig. 3; and

Fig. 7 is a cross sectional view of the upper or stack portion of the cupola.

The cupola frame consists of four vertical columns, which rest in and are fastened to cast iron bases 3, and to the upper end of which a platform frame 4, composed of channel iron, is secured. My novel cupola in this instance comprises three parts, to-

wit: a lower part 5, an intermediate part 6, and an upper part 7. I shall hereinafter refer to these parts respectively as, the tilting section, the charging door section, and the stack section. I support the charging door section 6 from the platform frame 4 by means of a plate or annulus 10, which rests upon the channel iron and extends inwardly as is best shown in Figs. 3 and 6. The shell 90

11, and lining 12, of the charging door section both rest upon the member 10 while the depending portion 13 is carried by ears 14 depending from the member 10 and fastened to the furnace shell. The tilting sec-

tion is supported upon steel bars 15 which span the columns and are secured thereto by means of trunnions 16. The trunnions 16 are of special design, having a large central opening for the admittance of the air inlets 100

17 which communicate with the boxes 18 secured to the shell of the tilting section. I locate the trunnions in such position that the section carried thereby is well balanced 105

to enable easy swinging movement thereof. In order that the air may be spread throughout the entire cross sectional area of the furnace, I provide nozzles 19, of novel construction, for conducting air from the boxes 18 into the furnace. These nozzles, 110 as is best shown in Figs. 4 and 5, have a relatively large cylindrical opening at the

air box end and taper to a relatively long narrow mouth 20 at the furnace interior. By this nozzle construction I am able to spread the air throughout the entire cross 5 sectional area of the furnace, as is indicated by the arrows in Fig. 4, and thus to produce a cross sectionally even combustion of fuel and uniform melting of the iron. The importance of uniform presentation of air 10 to the fuel cannot be overestimated.

In order that the actual operation of the furnace may be observed by the students, I provide a sight opening 21 adjacent the lower end of the furnace. This sight opening 15 greatly assists the students in understanding the conditions and phenomena of cupola practice.

In the upper end of the lower or tilting section and in the lower end of the intermediate section, I provide complementary sloping or angling faces 22 and 22' respectively, so that a tight joint may be formed when the parts are positioned for melting. The lining 12 of the section 6 is supported 25 independently by means of the inwardly extending flange 24 which is supported on the platform 4, as is best shown in Fig. 6. Where it is necessary or desirable to use an additional straight or elbow stack, I support 30 it by means of a ring 25 which is secured to the charging door section and which has an inwardly extending flange 26 which supports the elbow shell as well as the lining 27. Thus the lining of the elbow, and in fact 35 the lining of all parts of the furnace, is supported independently of the lining of the other parts and can, therefore, be repaired without in any way interfering or affecting the lining of such other parts. This is a great practical convenience and is of especial service where the cupola is to be lined 40 and chipped by students of average ability.

By tilting the lower section of the furnace it is possible easily and conveniently to 45 repair the lining and to lecture to a large number of students upon the interior or

working parts of the cupola; to describe and actually point out the arrangement and construction of the twyer system; the location of the melting zone; the action of heat and fluxes on the lining; and the method of chipping out and daubing the furnace. On the other hand, when the furnace is in melting position, it is to all intents and purposes as effective as a furnace of the standard commercial type, that is to say, all the conditions and phenomena met in commercial cupola practice are accurately reproduced but on a scale suited to the needs of a school foundry. 50 55

It is thought that the foregoing detailed description will enable those skilled in the art to which this appertains to make and to use the same. Inasmuch, however, as various modifications will readily suggest 60 themselves to those skilled in the art, I do not wish to be limited to the precise structure shown and described, except as may be necessary by limitations in the hereunto appended claim. 65 70

I claim:

In a cupola of the character described, the combination of a tilting section, an intermediate section and a stack section arranged in superimposed vertical alinement, said intermediate and tilting sections having sloping contiguous faces whereby said tilting section can be swung to and from said intermediate section without elevating the intermediate section, means for separately and independently supporting brick lining in each section, trunnions on which the tilting section is carried, and air conduits entering the tilting section through said trunnions. 75 80

In testimony whereof, I have hereunto set 85 my hand, this 28th day of December, 1915, in the presence of two subscribing witnesses.

GEORGE A. ROSS.

Witnesses:

ARTHUR WM. NELSON,
JOHN R. LEFEVRE.
